UNITED STATES PATENT OFFICE.

ALFRED BURGE, OF GARY, INDIANA, ASSIGNOR TO NATIONAL TUBE COMPANY, A CORPORATION OF NEW JERSEY.

TAPPING-MACHINE CHUCK.

Application filed April 7, 1926. Serial No. 100,444.

This invention relates to a chuck for use in tapping machines and the like, the general object of the invention being to provide the gripper casing with a movable section, 5 with an eccentric for moving the section to grip the article to be operated upon.

This invention also consists in certain other features of construction and in the combination and arrangement of the several 10 parts, to be hereinafter fully described, illustrated in the accompanying drawings and specifically pointed out in the appended claims.

In describing my invention in detail, reference will be had to the accompanying 15 drawings wherein like characters denote like or corresponding parts throughout the several views, and in which:—

Figure 1 is a plan view of the device.

Figure 2 is a vertical sectional view 20 through Figure 1.

Figure 3 is a section on line 3—3 of Figure 2.

Figure 4 is a view of the movable section or block.

25 Figure 5 is a view of the eccentric and its shaft.

Fig. 6 is fragmentary bottom plan view of the device.

In these views, 1 indicates the outer casting which is interiorly shaped to receive the gripper 2 which is designed to hold the article to be operated upon. There would be a plurality of these grippers, the opening in which would be of varying diameters 30 so that various sizes of objects can be held in the device by using the gripper of the size to hold the object to be operated upon. Each of these grippers is formed with an opening 3 in one end thereof to receive a 35 movable block or section 4, the curved part of which forms a movable wall of the gripper so that by moving said block or section inwardly, an object will be clamped by the gripper. Recesses 5 are formed in 40 the walls of the gripper and in the block 4 to receive the teeth 6 which engage the object placed in the gripper. A screw shaft 7 has threaded engagement in a hole 8 formed in the center of the block and the outer wall 45 of the block is recessed, as at 9, to receive a knurled disk 10 which is attached to the outer end of the shaft 7. A shaft 11 is rotatably mounted in the casting 1 and has an eccentric 12 thereon. The outer end of 50 the shaft is provided with a square part 13

for engagement by a wrench so that the shaft can be rocked. A bushing 14 is threaded in the casting 1 and holds the eccentric shaft in position. A cross head 15, recessed to receive the eccentric 12, is carried by the casting 1 and will engage the outer end of the shaft 7 when it is forced inwardly by the eccentric and thus the block or section 4 can be moved inwardly by turning of the eccentric shaft. The shaft 7 provides means for adjusting the extent of movement of the block by the eccentric. 60

From the foregoing, it will be seen that the block 4 can be moved into clamping position in order to clamp an object in the 70 device by a simple movement of the eccentric shaft and the movement of the block can be regulated by the turning of the shaft 7 through means of the knurled disk 10. 65

The drawings show the device used on a 75 rotary chuck used for tapping couplings where the tap is held stationary, but it will, of course, be understood that the chuck could be held stationary and the tap rotated, if desired. 80

It is thought from the foregoing description that the advantages and novel features of my invention will be readily apparent.

I desire it to be understood that I may make changes in the construction and in the 85 combination and arrangement of the several parts, provided that such changes fall within the scope of the appended claims.

What I claim is:—

1. A device of the class described comprising a support, a gripper removably seated in the support and having an opening therein, a block or section movably arranged in said opening and having a curved inner portion which forms a movable wall for the gripper, 90 an eccentric for moving the block or section and means for adjusting the extent of movement of the block by the eccentric. 95

2. A device of the class described comprising a support, a gripper arranged therein, 100 said gripper having an opening therein, a block or section movably arranged in the opening, a screw shaft carried by the block, means permitting turning movement of the shaft, a cross head in the support and engaging the outer end of the shaft, an eccentric shaft in the support and an eccentric thereon engaging the cross head. 105

In testimony whereof I affix my signature.

ALFRED BURGE.
